UNITED STATES PATENT OFFICE.

FREDERICK J. NORRIS, OF FALL RIVER, MASSACHUSETTS, ASSIGNOR TO DRAPER CORPORATION, OF HOPEDALE, MASSACHUSETTS, A CORPORATION OF MAINE.

LENO OR CROSS-WEAVING LOOM.

1,416,410.

Specification of Letters Patent. Patented May 16, 1922.

Application filed November 3, 1921. Serial No. 512,605.

To all whom it may concern:

Be it known that I, FREDERICK J. NORRIS, a citizen of the United States, residing at Fall River, in the county of Bristol and 5 State of Massachusetts, have invented an Improvement in Leno or Cross-Weaving Looms, of which the following description, in connection with the accompanying drawings, is a specification, like characters on 10 the drawings representing like parts.

The invention to be hereinafter described relates to looms and more particularly to leno or cross-weaving looms wherein certain of the warp threads are crossed back 15 and forth relative to other warp threads to produce the cross-woven effect.

In looms of this general character as heretofore constructed, the complicated nature of the mechanism employed and its manner 20 of operation introduced much uncertainty in the loom action and necessitated the frequent stoppage of the loom to correct faults incident to the character of the mechanism employed. One of the objects of the 25 present invention is to simplify the cross-weaving mechanism, and provide a loom of the type indicated which will be more efficient and reliable in operation and wherein the loom may be run continuously without 30 the frequent stoppage heretofore necessitated.

The warp threads which are involved in the production of the leno or cross-weave are generally known as the "doup" threads and 35 the "ground" or "dead" threads; and these terms will be used herein for convenience of identification.

In accordance with the present invention, a simple unit comprising the cross-weave 40 consists of two doup threads and a ground thread, and a description of the invention in this connection will serve to make more clear the construction and operation thereof; but it is to be understood that each doup thread 45 and each ground thread may comprise more than a single thread in conformity with the character of the cross-weave effect desired. In some cases, also, the cross-weave effect in the finished fabric may extend throughout 50 its entire width, while in other cases, it may be utilized in forming cross-weave effects in strips, more or less pronounced, and of any desired extent.

In carrying the invention into practical 55 effect, each of the doup threads is controlled

by a separate doup heddle and both doup threads pass through a floating eye between the doup heddles and the lay. The ground thread is controlled by two ground heddles, one of which and one of the doup heddles 60 operate as a pair, and the other of which and the other doup heddle operate as another pair in the formation of the shed with the ground thread always in the same 65 shed plane. The doup and ground threads lead from a source of supply over a guide to the heddles and in the formation of the 70 shed one of the doup heddles tensions its doup thread in advance of the other doup heddle to carry the floating eye and both 75 the doup threads first to one side and then to the other of the ground thread in successive shed formations.

In the drawings:

Figure 1 is a perspective view of sufficient 75 portions of a loom with the present invention associated therewith, to make clear the construction and mode of operation of the invention;

Figure 2 is a partial diagrammatic view 80 showing one means for effecting tension on one of the doup threads in advance of the other as the shed is formed;

Figure 3 is a plan view of a piece of fabric 85 woven with the leno or cross-weave effect;

Figure 4 is an enlarged perspective detail showing the relation of the doup and ground threads when they are in substantially a position for the commencement of the shed formation; and 90

Figure 5 is a view similar to that of Fig. 4, with the shed formed and showing both doup threads at one side of the ground thread.

In the illustrated form of the invention 95 as indicated in Fig. 1, the loom is equipped for weaving a fabric having portions only thereof formed of cross-weave, while the intermediate portions may be woven either in plain or any desired figure effect.

Having reference more particularly to Fig. 1: the loom frame 1 may be of usual construction and provided with bearings 2 for the support of a warp beam 3 on which the main or body warp threads *d* may be wound. 105 Where a portion of the fabric is to be formed of plain or figured effect, from the body warp threads *d*, the latter pass from the beam 3 over the usual whip-roll 4 over and under the usual lease rods 5 to the body- 110

forming heddles 6, of which there are four in the illustrated form of the invention, but which may be varied to suit the character of figure effect desired in the body of the 5 fabric. The heddles 6 may be operated to form the shed of the body fabric by any of the usual mechanisms now generally employed for this purpose, such for instance, as the usual dobby or cam mechanism; and 10 as such construction and manner of operation of the body-forming heddles are old and well known, it will not be necessary to enter into a detailed description thereof. From the heddles 6 the body warp threads *d* pass 15 through the reed 7 carried by the lay 8, as usual.

A unit of the leno or cross-weave comprises three threads, one ground thread *a* and two doup threads *b*, *c*, which may be 20 supplied from a source of supply such, for instance, as the overhead beam 9, Fig. 1. The beam 9 which carries the supply of the doup and ground threads in the present instance, is supported by bearings 10 extending 25 from uprights 11 rising from the loom frame. The beam 9 has one or both its heads grooved as at 12, for the reception of a brake-band 13 which may be tensioned by means of a spring 14 interposed in the length 30 of the band. The brake-band 13 constitutes one type of a friction let-off for the beam 9, and in the present instance is connected to a cross-frame 15 extending transversely of the loom. The frame 15 in the present 35 instance consists of one of the loom arches which offers a convenient means for supplying a friction brake to the overhead beam 9.

From the beam 9 the doup and ground threads pass over a guide 16 extending trans- 40 versely of the loom and supported by the brackets or arms 17 at each end. The guide 16 is fixed or immovable and constitutes a directing means from the overhead beam 9 for the doup and ground threads.

45 Each of the doup threads *b* and *c* is controlled by a separate heddle with eyes through which the doup threads pass, and the ground thread *a* is controlled by the two ground heddles, one operating with one of 50 the doup heddles and the other operating with the other doup heddle.

The heddle frames 18 and 19, which in the present instance of the invention, control both the doup threads and ground thread, 55 carry the heddles 20 and 21 respectively, each of which is provided with an eye 22 through which is passed one of the doup threads.

60 Mounted adjacent each of the doup heddles 20 and 21 is a ground heddle 23 each having an elongated loop 24 through both of which passes the ground thread *a*, the construction being such that upon the formation of a shed, one of the doup threads is raised and 65 the other lowered, and the ground thread, in

the present instance, accompanies the up-going doup thread. Of course if the ground thread were passed through the lower loop 25 of the ground heddles, the ground thread would accompany the downgoing doup 70 thread. The two doup threads *b* and *c* pass through a floating eye 26 between the reed 7 and the heddles, the result being that in the formation of the shed both the doup threads are carried to the same shed plane while the 75 ground thread is carried to the opposite shed plane.

The heddles 18 and 19 are normally under the influence of springs 31, and are connected to the shed-forming mechanism by usual flexible connections or straps 27 which pass over the usual guide rolls 28 carried by the loom arch, and thence to the shedding mechanism. In the invention as shown, the shedding mechanism is in the form of a 80 dobby comprising the arms 29 and 30 to which the connections 27 are secured. Since the dobby or other form of shedding mechanism is of the usual and well-known construction, only so much of the shedding 85 mechanism is shown as is necessary to indicate the shed-forming operation.

The present invention contemplates that the crossing of the threads shall be effected 90 through the operation of the heddles and without interposition or inclusion of special mechanism. To this end one of the doup heddles and its associated ground heddle may be started in advance of the other doup heddle and its associated ground heddle in order that tension may first be placed upon one doup thread to cause both to pass to the same side of the ground thread; or the shed may be started from a position above 95 or below the horizontal plane passing through the guide 16 to the fell of the cloth. In the present instance the change of shed is shown as being started from a plane below the horizontal plane between the guide 100 16 and the fell of the cloth, as in Fig. 2, so that upon the formation of the shed, the downgoing doup thread is first tensioned while the other doup thread is slack or slackened by the upgoing heddle, the effect 105 being that the downgoing doup thread pulls the floating eye 26 and with it the other doup thread, to its side of the ground thread as indicated in Fig. 5. Similarly, in the formation of the next shed, the downgoing doup thread will be tensioned while the other doup thread is slack or slackened, with the result that the floating eye 26 and the 110 other doup thread will be pulled to the opposite side of the ground thread, as in Fig. 6.

115 The heddles 18 and 19, which in the present instance of the invention, control both the doup threads and ground thread, 120 carry the heddles 20 and 21 respectively, each of which is provided with an eye 22 through which is passed one of the doup threads.

125 Mounted adjacent each of the doup heddles 20 and 21 is a ground heddle 23 each having an elongated loop 24 through both of which passes the ground thread *a*, the construction being such that upon the formation of a shed, one of the doup threads is raised and 130 the other lowered, and the ground thread, in

by crossing the doup threads relative to the ground thread and producing with the binding weft or filling thread *e*, Fig. 3, the leno or cross-weave effect.

5 The threads *a*, *b*, *c*, constituting the leno or cross-weaving threads, may be passed from the fixed guide bar 16 frontwardly over and under the usual lease rods 5, and then to their respective heddles as above indicated.

10 In the construction shown, the doup threads *b* and *c* are passed alternately over the ground thread *a* in forming the shed, and the ground thread *a* always is found in the 15 same shed plane which is the upper plane in the present instance of the invention. The same effect, however, would be produced if the doup threads *b* and *c* were alternately passed under the ground thread *a* to one 20 side or the other thereof, in which case the ground thread *a* would always be in the lower shed and the doup threads *b* and *c* always in the upper shed. Thus, from the construction described it will be noted that 25 without the employment of easing bars or special tensioning devices for alternately giving up and taking back slack on the doup or ground threads, the present invention provides a simple, effective and reliable 30 means for the production of leno or cross-weave effect by the simple operation of one of the doup heddles and one of the ground heddles as a pair, and the other doup heddle and the other ground heddle as another pair, 35 and the tensioning of one of the doup threads in advance of the other in the formation of a shed.

What is claimed is:—

1. In a cross-weaving loom, the combination of two doup heddles each having an eye 40 for a doup thread, two ground heddles each controlling a single ground thread, a floating eye through which both doup threads pass, and means for operating one of the doup 45 heddles and one of the ground heddles as a pair and the other doup heddle and other ground heddle as another pair to form the shed with the ground thread successively placed in the same shed plane and for crossing 50 the floating eye and both doup threads first to one and then the other side of the ground thread.

2. In a cross-weaving loom, the combination of two heddle frames, each having a 55 doup heddle provided with an eye for a doup thread, a ground heddle carried by each of the heddle frames and provided with an elongated loop through both of which passes the same ground thread, a floating eye 60 through which both of the doup threads pass, and means for operating the heddle frames to form the shed with the ground thread always in the same shed plane and to cause the floating eye and both doup threads 65 to cross the ground thread.

3. In a cross-weaving loom, the combination of two doup heddles each having an eye for a doup thread, a floating doup eye through which the two doup threads pass, a ground heddle operating with each of the 70 doup heddles and each having a loop for a single ground thread, and means for operating a doup heddle and ground heddle in pairs to form the shed and tension one of the doup threads in advance of the other to 75 cause the floating doup eye and both doup threads to cross the ground thread.

4. In a cross-weaving loom, the combination of two doup heddles each having an eye for a doup thread, a floating doup eye 80 through which both doup threads pass, two ground heddles each having an elongated loop through both of which a ground thread passes, and means for operating a doup heddle and one of the ground heddles in pairs to 85 form the shed with the ground thread always in the same shed plane and to cause the floating doup eye and both doup threads to cross the ground thread.

5. In a cross-weaving loom, the combination of two doup heddles each having an eye for a doup thread, two ground heddles each controlling a single ground thread, a floating eye through which both doup threads pass, 90 fixed guiding means for guiding the doup and ground threads to the heddles from a source of supply, and means for operating one of the doup heddles and one of the ground heddles as a pair and the other doup heddle and other ground heddle as another 95 pair to form the shed with the ground thread successively placed in the same shed plane and for crossing the floating eye and both 100 doup threads first to one and then the other side of the ground thread.

6. In a cross-weaving loom, the combination of two doup heddles each having an eye for controlling a doup thread, a floating eye through which both the doup threads pass, two ground heddles each having a loop for 110 controlling a single ground thread, a guide for guiding the two doup and single ground threads from a source of supply to the heddles, means for operating one of the doup heddles and one of the ground heddles as a pair and the other doup heddle and ground heddle as another pair to form the shed from a position at one side of the horizontal plane between the guide and fell of the cloth that one of the doup threads may be tensioned in 115 advance of the other and cause the floating eye and both doup threads to cross the ground thread.

7. In a loom of the character described, the combination of two heddles each having 125 an eye for controlling a doup thread, two ground heddles, one adjacent each of the doup heddles and both controlling a single ground thread, a floating eye through which both of the doup threads pass, means for 130

guiding the doup threads and ground thread from a source of supply to the heddles, and means for operating one of the doup heddles and one of the ground heddles as a pair and 5 the other doup heddle and other ground heddle as another pair in the formation of the shed with the ground thread always in the same shed plane and for tensioning one doup thread in advance of the other to cross the 10 floating eye and both doup threads relative to the ground thread.

8. In a loom of the character described, the combination of two heddle frames each having a doup heddle provided with an eye 15 for controlling a doup thread, two ground

heddles, one carried by each of the heddle frames adjacent the doup heddle of that frame and both controlling a single ground thread, a floating eye through which both doup threads pass, a fixed guide for guiding 20 the doup threads and ground thread from a source of supply to the heddles, and means for operating the heddle frames to form the shed and cause one of the doup threads to pull the floating eye and the other doup 25 threads across the ground thread.

In testimony whereof, I have signed my name to this specification.

FREDERICK J. NORRIS.
